UNITED STATES PATENT OFFICE

ILLIE FULLER, OF MADISON, SOUTH DAKOTA

GARMENT HANGER

Application filed October 1, 1931. Serial No. 566,347.

This invention relates to certain new and useful improvements in garment hangers, and the primary object of the invention is to provide a hanger especially adapted for use with men's trousers.

Briefly, the invention consists in the provision of a hanger having two identical members each of which is insertable in a leg of the trouser and expansible for retaining the 10 trouser in a creased condition.

Other objects and advantages of the invention, together with the nature of the invention will be best understood from a study of the following description, taken in connection with the accompanying drawings wherein:

Figure 1 is a side elevational view of the hanger, the same being shown as employed for suspending trousers therefrom.

20 Figure 2 is an end elevational view of the hanger in a folded condition.

Figure 3 is a top plan view of the hanger with the same in an unfolded or fully extended position.

25 In the preferred embodiment of the invention, and as shown in the drawings, the hanger consists of a plate 5 equipped with a suspension hook 6. The plate 5 is rolled upon itself adjacent its opposite longitudinal edges or otherwise formed to provide a pair 30 of parallel sleeves 7. Two similar members designated 8 and 9 respectively are provided, and each of these members is of general U-shape, being formed of wire or other suitable material.

Each of said members 8, 9 at the bight or closed end thereof has the connecting portion 10 extending through a sleeve 7 for pivotally connecting the member with the plate 40. 5. Opposed portions 11 are curved longitudinally, and adjacent opposite ends reversely curved as at 12 and 13. The reversely curved end 13 of each portion 11 is coiled about itself as at 14, the coil forming as it were a 45 spring connection between the part 10 and a side member 11 for normally urging the member outwardly.

The reversely curved portion 13 merges 50 into an arm or extension 15 extending laterally and outwardly and terminating in a

downwardly extending flattened projection 16 provided on its outer longitudinal face with a roughened surface 17. The surface 17 may be formed by corrugating the member 16, or otherwise formed to provide projections which are suitable for engaging the cloth of the trouser without damaging it.

In actual practice, each of the members 8 and 9 is passed into one leg of the trouser at the cuff end thereof as shown in Figure 1. In 60 inserting a member 8 or 9 in a leg of the trouser, the parts 13 of the sides 11 are engaged with the thumb and forefinger and urged inwardly toward one another for contracting the U-shaped member to facilitate 65 insertion thereof into the trouser leg. Pressure is then removed from the portion 14, permitting the sides 11 to spring outwardly from one another and the extensions 16 are received between opposed sides of the trouser 70 leg at the front and rear creases thereof.

Thus the presser is stretched sufficiently to retain the trouser extended throughout its length which serves to retain the crease in the trousers at the front and rear thereof 75 while the same is suspended from the hanger. The surfaces 17 engaging the adjacent portion of the trouser present the latter from slipping downwardly because of the weight thereof. To remove the trouser from the hanger, it is only necessary to first contract the members 8 and 9 and then draw the same 80 outwardly from the legs of the trouser.

Even though I have herein shown and described the preferred embodiment of the invention, it is to be understood that the same is susceptible of further changes, modifications and improvements coming within the scope of the appended claims.

Having thus described my invention, what I claim as new is:

1. In a garment hanger, a plate provided with a pair of parallel sleeves, a pair of U-shaped members each of which at its closed end is rotatably engaged with one of said sleeves, each of said U-shaped members having opposed portions thereof arcuate intermediate its ends and reversely curved adjacent its ends.
2. In a garment hanger, a pair of U-shaped

members pivotally connected together adjacent the closed ends thereof, each of said U-shaped members having opposed longitudinally curved portions reversely curved adjacent the open and closed ends of the U and at the closed end being coiled while at the open end of the U merging into a laterally directed extension having an angularly disposed toothed end.

10 In testimony whereof I affix my signature.
TILLIE FULLER.
